UNITED STATES PATENT OFFICE.

NICHOLAS A. ELLIN, OF PROVIDENCE, RHODE ISLAND, ASSIGNEE TO EKELUND BROTHERS, OF PROVIDENCE, RHODE ISLAND, A FIRM.

CLASP.

Application filed April 24, 1922. Serial No. 556,218.

To all whom it may concern:

Be it known that I, NICHOLAS A. ELLIN, a citizen of the United States, residing at Providence, in the county of Providence and State of Rhode Island, have invented certain new and useful Improvements in Clasps, of which the following is a specification.

My invention relates to a clasp for necklaces and other articles of jewelry, and has for its essential objects the prevention of complete detachment of the clasp parts when the parts are accidentally partially disengaged, and to the attainment of this end in an inexpensively constructed, strong, slightly device.

To the above ends essentially my invention consists in such parts and in such combinations of parts as fall within the scope of the appended claim.

20 In the accompanying drawings which form a part of this specification,

Figures 1, 2, and 3 are a front elevation, a rear elevation, and a plan view respectively of a clasp embodying my invention,

25 Figures 4 and 5, sections on line 4—4 of Figure 3, showing the parts in locked and in semiengaged positions respectively, and

Figure 6, a section on line 6—6 of Figure 5.

30 Like reference characters indicate like parts throughout the views.

In its present and preferred form of embodiment my invention comprises a housing casing 8 comprising a front wall 9, a rear wall 10, and an elliptical periphery or side wall 11 uniting the same.

Fast to one end of the casing 8 by solder or otherwise is an attaching ring 13. At the other casing end is a slot 15 in the side 11. 40 This slot is continuous with a longitudinal opening 16 in the rear wall communicating centrally of a transverse opening 17. The openings 16 and 17 constitute a T shaped slot.

45 The locking member 19 of the clasp comprises a transverse strip 20 centrally of whose edge extend two normally spaced laterally resilient preferably diverging arms 21

having upon their free ends lateral fingers 23, upon one of which is an attaching ring 50 24. The parts 20, 21, 23, and 24 are integrally connected and cut from a single thin metal blank. The laterally projecting locking strip 20 is initially insertable into the casing by passing through the opening 17 55 which is narrower than the strip but of slightly greater length. Hence in inserting the strip the arm 21 must be disposed at an angle to the plane of the back 10. After the portion 20 enters the casing the arms 21 60 are next moved into the plane of the casing through the slot 15, which is slightly broader than the combined width of the arms, and into slot 15. The member 19 is next pushed inwardly through the slot 15 whereby the 65 arms 21 are compressed by the bounding edges 27 of the side wall until said edges snap into the notches 26, whereby the parts are retained in locked position.

If the parts are accidentally detached such 70 detachment is incomplete as shown in Figure 5, because the strip 20 engages the interior of the side wall 11. The fingers 23 are manually compressed where it is sought to detach the parts, and a reversal of the 75 above described steps completely separates the clasp parts.

I claim:

In a jewelry clasp, a casing comprising a front wall, a back wall provided with a 80 T shaped slot, and a peripheral wall provided with a transverse slot registering with the first slot, and a locking member comprising a transverse strip within the casing, laterally yielding arms integral with one 85 lateral edge of the strip slidable through the transverse slot and provided with lateral notches adapted to receive portions of the peripheral wall bounding said slot, fingers on the free ends of the arms, an attaching 90 ring supported by one of the arms, and an attaching ring on the casing.

In testimony whereof I have affixed my signature.

NICHOLAS A. ELLIN.
